BOILER CONNECTION

Original Filed Dec. 4, 1926

UNITED STATES PATENT OFFICE

VALENTIN WILHELMI, OF MAYWOOD, NEW JERSEY

BOILER CONNECTION

Original application filed December 4, 1926, Serial No. 152,567. Divided and this application filed April 26, 1927. Serial No. 186,604.

This invention relates to boiler connections such as shown and described in my co-pending application filed December 4th, 1926, Serial No. 152,567, of which this application 5 is a division, and more particularly to the connecting elements used on domestic hot water boilers by which the hot and cold water pipes are attached thereto.

Heretofore in the production of boilers for 10 domestic purposes, it has been customary to use galvanized iron for the boiler body or shell. Bosses were welded at desirable points thereon and were subsequently drilled and tapped for the introduction of the piping 15 connections. Such boilers have proven highly satisfactory for the purpose, but owing to the iron used in their construction, such boilers need frequent draining to remove rust particles therefrom. As a consequence, copper 20 boilers have been frequently substituted in the better class of installations, but owing to the nature of the material, the welding of the bosses thereon could not be accomplished and threads of sufficient length to form a 25 leak proof joint could not be produced.

It is the primary object of this invention to provide a connection between a boiler and the plumbing system which will permit of the use of copper for the body of the boiler, 30 by reinforcing the boiler shell at the points of introduction of the connecting pipes and at the same time facilitate the production of threads of sufficient length to produce a leak proof joint.

35 A feature of the invention is the annular flange formed on the boiler shell which enters an annular groove in the spud clamping element to center the spud relative to the opening in the shell and also serves as a seal to 40 prevent the escape of the water.

Another feature of the invention is the 45 annular cavity or channel surrounding the spud for the reception of the spud flange and the solder by which any space between the spud and shell is completely sealed and the entire area reinforced.

With the above and other objects in view 50 which will become more apparent as the description proceeds, one embodiment of the invention consists in the novel construction,

combination and arrangement of parts which will be fully set forth in the following specification and illustrated in the accompanying drawing, in which:—

Figure 1 is a vertical section, with parts 55 shown in elevation of a boiler of improved construction with the connections forming part of the present invention,

Figure 2 is an enlarged fragmentary sectional view through a portion of the boiler shell and connection with the parts in the 60 disassembled condition,

Figure 3 is a fragmentary vertical section showing a slight modification, and

Figure 4 is also a sectional view greatly 65 magnified and taken at one side of the joint, shown in Figure 3.

Referring more particularly to the drawings 5 designates the boiler shell of cylindrical or other form having the heads 8 and 9. 70 rivets 11 being employed to pass through the overlapped parts for securing the heads to the boiler.

The heads 8 and 9 are centrally perforated and provided with an out-turned flange 20 75 adapted to be received into the annular channels 21 in the inner sides of the nuts 22 provided with the internal screw threads 23 to co-operate with the external threads 24 upon the intermediate body portion of the spud or connection, indicated generally at 25. The spuds 25 are provided with the flanges 26 80 preferably of wedge form in cross section and having their outer free ends tapered to substantially an edge. Such flanges 26 are adapted to be received into the cavities provided by outwardly offsetting the central portions 27 of the heads about the openings through which the spuds pass, and the inclined inner walls 28 of the flanges 26 co- 85 operate with the opposite mutually inclined walls of the depressions to provide substantial spaces for receiving a body of solder 29 useful to bind the spud to the boiler head and also to make a tight and leak proof joint. 90

The nut 22 will bind a portion of the head next the flange 20 against the flange 26 of the spud connection and will thus form a tight fit between these parts, and the engagement of the flange 20 itself in the groove 21 100

of the nut will further contribute to form a tight joint.

If desired, when the assembly of the parts has been performed and before the nut 22 has been tightened to any great extent solder 5 may be flowed into the depression referred to and, due to the looseness of the parts, it will find its way down to the space at the inner side of the flange 20 and will also creep 10 into the channel 21 of the nut. The nut may be tightened before the solder sets. The body 29 of the solder on the interior forms also a smooth joint with adjoining parts of the boiler head and spud connection.

15 In Figure 1 the top spud is shown as carrying the internal pipe 30 while the spud also provides for receiving an external pipe connection. In this instance the body of the spud is made of substantially the same diameter and the intermediate threads 24 are continued upwardly to the end of the spud.

20 In the case of the lower spud, which is also more particularly illustrated in Figure 2, the inner portion of such spud is of greater diameter than the lower portion 31, there being an intermediate inverted frusto-conical connecting portion 32 having an outer blank wall.

25 The exterior wall of the outer reduced portion 31 is preferably threaded, as indicated at 33 to receive the binding nut for a pipe.

30 Referring more particularly to Figures 3 and 4, the boiler head is indicated at 9^a and is of slightly modified construction in that 35 the depression 27 is omitted and the wall of the head is carried outwardly in a more or less sweeping curve to provide the flange 20^a, which extends about the opening through which the spud connection 25^a is inserted. 40 The nut 22^a is of substantially the same construction having the channel 21^a to receive the outer annular end of the flange 20^a. The nut 45 engages the external threads upon the spud 25^a. Such spud is also of modified construction in that its inner portion 34 is arranged to be bent against the adjacent portion of the head 9^a or flange 20^a. The original position of the end 34 is shown at 34^a in dotted lines.

50 After assembly, and when a body of solder 35 has been flowed into the cavity between the spud connection and the flange 20^a, the inner end 34 of the spud is bent over, as by rolling to the position, shown in full lines, whereupon the body of solder is shoved tightly 55 between the parts referred to and downwardly against the nut face and also possibly into the channel 21^a, thus forming a tight joint between the threads and between the channelled and flanged parts. Provision is 60 made for holding a substantial body of the solder in order to add strength to the construction. In assembling the parts, the work done upon the spud joint as to assembling it is accomplished before the heads 8 and 9 are 65 put upon the boiler whereby the solder may

be flowed into the depression 27 when the depression is uppermost for this purpose and when access can be easily had to the same. After the spud connections are in place the heads may be united with the boiler and the 70 reinforcing bands 16 and 17 sweated or otherwise put in place. The boiler is then ready for use and when installed the pipe connections will be fitted thereto in the usual manner.

75 I have illustrated and described a preferred and satisfactory embodiment of my invention, but it is obvious that changes may be made therein within the spirit and scope thereof as defined in the appended claims.

80 What is claimed is:—

85 1. A boiler connection comprising, in combination with a boiler having an opening with an out-turned flange, a spud connection to said boiler, and a nut upon the spud connection and having a channel spaced from the threaded opening of the nut for receiving said flange.

90 2. In combination with a boiler head, having an outwardly pressed wall section provided with an opening therethrough, a spud having a tubular body of appreciably less external diameter than said opening for loose insertion therethrough and said spud wall having a surrounding radially tapering 95 flange to seat against the inner face of said outwardly pressed wall section, a body of joint forming metal filling the internal space provided by said outwardly pressed wall section and overlying the tapering flange on the spud wall to seal the latter against the boiler head, a nut threaded upon the spud exteriorly of the boiler head, and said nut and the wall of the boiler head being provided with co-acting means to prevent radial displacement of the spud relative to said opening.

100 In testimony that I claim the foregoing as my invention, I have signed my name hereto.

105 VALENTIN WILHELM.
